UNITED STATES PATENT OFFICE.

WILLIAM T. SMITH, OF PHILADELPHIA, PENNSYLVANIA.

DESIGN FOR A RUG.

SPECIFICATION forming part of Design No. 17,033, dated December 21, 1886.

Application filed October 7, 1886. Serial No. 215,624. Term of patent 3½ years.

To all whom it may concern:

Be it known that I, WILLIAM T. SMITH, a citizen of the United States, residing at Philadelphia, in the county of Philadelphia, and 5 State of Pennsylvania, have invented and produced a new and original Design for a Rug; and I do hereby declare that the photographic print accompanying this specification conveys to any one skilled in the art a clear understanding of the same, and is sufficient to enable such persons to use my invention.

The leading features of my design consist in a center panel having narrowed and right-angled extended ends B B. This panel is or- 15 namented by the representation of the upper part of a vase holding a bunch of flowers, showing long leaves and sprays of small flowers, which are shown on a background represented as laid in mosaics, the extremities of 20 the rug being ornamented by a representation of leaves and flowers. At D D are shown representations of begonia-leaves.

The top, part of the bottom, and upper ends of the rug are ornamented by a border formed of flowers, as shown. 25

What I claim as my invention is—

The design for a rug, consisting of a center panel having narrowed and right angular extended ends B B, and ornamented by the upper part of a vase, a bunch of flowers, and leaves, shown on a mosaic ground, the extremities of the rug being ornamented by flowers and leaves, showing begonia-leaves at D D, the top, part of the bottom, and upper corners of the rug ornamented by borders formed of 35 flowers, the whole as shown in the photographic print.

W. T. SMITH.
